US00D810118S

(12) **United States Design Patent** (10) Patent No.: US D810,118 S
Chen et al. (45) Date of Patent: ** Feb. 13, 2018

(54) DISPLAY SCREEN WITH GRAPHICAL USER INTERFACE

(71) Applicant: **Microsoft Corporation**, Redmond, WA (US)

(72) Inventors: **Xiaoji Chen**, Seattle, WA (US);
Benjamin Perry, Redmond, WA (US);
Emmanuel Reyes, Lynnwood, WA (US); **David Gardner**, Covington, WA (US); **Mengyuan Tu**, Seattle, WA (US); **Jeff Fleischmann**, Seattle, WA (US)

(73) Assignee: **Microsoft Corporation**, Redmond, WA (US)

(**) Term: **15 Years**

(21) Appl. No.: 29/551,696

(22) Filed: **Jan. 15, 2016**

(51) LOC (11) Cl. 14-04

(52) U.S. Cl.

USPC D14/487

CLAIM

The ornamental design for a display screen with graphical user interface, as shown and described.

DESCRIPTION

The FIGURE is a front view of a display screen with graphical user interface showing our new design. The broken line showing of the remainder of the user interface and the remainder of the display screen is for environmental purposes only and forms no part of the claimed design.

1 Claim, 1 Drawing Sheet
